UNITED STATES PATENT OFFICE

152,820

DESIGN FOR A BOTTLE

Leo G. Nunes, New York, N. Y., assignor to Conti
Products Corporation, Brooklyn, N. Y., a cor-
poration of New York

Application January 18, 1947, Serial No. 136,251

Term of patent 14 years

(Cl. D58—6)

To all whom it may concern:

Be it known that I, Leo G. Nunes, a citizen of the United States, residing in New York city, in the county of New York, in the State of New York, have invented a new, original, and ornamental Design for a Bottle, of which the following is a specification, reference being had to the accompanying drawing, forming a part thereof.

Figure 1 is a front elevation of a bottle embodying my new design.

Figure 2 is a side elevation,

Fig. 3 is a top view.

I claim:

The ornamental design for a bottle, as shown.

LEO G. NUNES.
